KNITTING DEVICE AND METHOD OF
KNITTING

Franz Melwald, Vienna, Austria

Application May 27, 1935, Serial No. 23,773

2 Claims. (CL 66—8)

My invention relates in particular to the type of knitted thread described and claimed in my U. S. Patent No. 2,006,275, of the subject matter, of which the present invention is a particular modification. The particular advantages of knitted strands such as, for instance, textile threads as compared with twisted strands, are referred to in detail in my aforesaid patent. In said patent I have described threads or strands knitted with a plurality of needles and threads and the manner of producing such threads. The present invention refers in particular to the knitting of at least two filaments with only one needle, whereby a very slender knitted yarn or strand can be produced which lends itself advantageously to the production of fabrics of any kind which heretofore were made of spun, twisted, or laid threads. Especially it is possible by the arrangement according to the present invention to produce many different effects with or without color in the appearance of the knitted yarn which are either impossible or difficult and expensive to produce with yarns which are twisted.

My invention is illustrated in the accompanying drawing, in which

Figure 1 represents an enlarged view of one form of knitted yarn according to the invention.

Figure 2 represents diagrammatically a knitting head by which the yarn shown in Figure 1 is produced.

Figure 3 represents, greatly enlarged, the looping of the filaments by the needle in order to produce the yarn shown in Figure 1.

Figure 4 represents a two filament yarn, knitted according to the invention having the loops of both filaments of substantially equal length;

Figure 4a represents two-filament yarn in which the loops of one filament are relatively long and those of the other filament are drawn into a tight knot;

Figure 4b represents two-filament yarn in which the loops of one filament are relatively long and those of the other filament are very short, but still open, and

Figure 5 represents a fabric which may be produced from the yarn according to the invention.

Referring to Figure 1, it will be noted that the yarn is composed of the two filaments 1 and 2 which are shaded light and dark, respectively. It will further be noted that the loops of the two filaments alternately follow one another. Where more than two filaments are used, they alternate in rotation. For instance, if there should be four filaments used, they would alternate in rotation 1—2—3—4, 1—2—3—4.

Referring more particularly to the yarn formed with two filaments as shown in Figure 1, it will be noted further that the float 3 which connects two successive loops of the light-shaded filament, passes through the intervening loop of the dark-shaded filament which connects the two successive loops of the first-mentioned filament. By this manner of interlocked knitting, a yarn is produced which is ravel-resisting.

Describing now the manner in which such a yarn may be produced with one needle, I refer to Figure 2 which shows the needle cylinder 4 mounted within the cam cylinder 5 which is provided with a cam groove 6 in which the foot 7 of the needle 8 is guided and by which the needle 15 is longitudinally actuated.

In the present form of Figure 2, it is assumed that only two filaments are being knitted with one needle. These two filaments 1 and 2 are guided to the needle 8 by means of the thread 20 guides 9 and 9a respectively which are suitably positioned so that the needle 8 may engage one or the other thread as the needle cylinder rotates.

As shown more clearly in Figure 3, in which the loop 1a of filament 1 is assumed to be readily formed, the needle has just passed through the new loop 2a formed with the thread 2 and has just hooked the filament 1 to form a new loop and to pull it through the previously formed loop 2a of filament 2. The interlocking of the loops 30 occurs thereby as follows: Assuming that the needle 8 has just formed loop 2a when in a position opposite to that shown in Figs. 2 and 3, and that it has come around into the position shown in these figures with loop 2a still hanging on the needle shank preparatory to its being cast off. Then it will be noted that filament 1 extends from the previously formed loop 1a as a float across loop 2a and in a position in which it can be engaged by the needle as shown in these figures. 40 When the needle 8 in Figs. 2 and 3 now descends to pull filament 1 through loop 2a the float of the loop formed by this filament will lay itself across loop 2a when the latter is cast off. It is assumed in the illustrations Figs. 2 and 3 that 45 the needle 8 travels away from the observer.

It will further be noted from Figure 2 that there are two high points in the cam groove 6, namely, one at the point where the foot 7 of the needle is shown and the other (not shown) at 50 the diametrically opposite side of the cam cylinder 5. The two high points of the cam groove correspond with the number of filaments which are knitted. If more than two filaments are to be knitted with one needle, more high points must 55

be used in the cam. In other words, there must be as many high points in the cam as there are filaments to be knitted together.

This manner of knitting yarn lends itself to a great variety of forms made with the same kind of stitch as, for instance, shown in Figures 1 and 2. As is illustrated diagrammatically in Figure 4, the loops of both filaments may be formed of equal length or approximately so, such as 1-2, 10 1-2. In the form shown in Figure 4a, one thread 10 may be formed with a long loop while the other thread 11 may be tightly knotted, i. e., its loop may be drawn tight together. This form produces the so-called "knob" yarn. Figure 4b 15 shows a form in which one loop 12 is left long and with the two shanks close together, while the other loop 13 is short and left open so that the yarn has the appearance of pearls, as it were, threaded onto a string. This yarn, so far as I 20 am aware, is known in the industry as "boucle" yarn, but has heretofore been produced by twisting in several different ways.

In Figure 5 I have illustrated a fabric which may be produced by any of the yarns described herein. It should be particularly noted with reference to boucle and similar yarns, that their production by twisting requires a large number of operations which must be successively performed.

30 According to the manner of knitting which I have described herein, the yarn is produced by one single knitting operation and the different character of the yarn, such as is shown for instance diagrammatically in Figures 4, 4a, and 35 4b, is produced merely by properly regulating the tension of the filaments as they are supplied through the thread guides. For instance, for yarn according to the modification Figure 4a, the thread-feeding device which supplies filament 10 40 supplies the filament very loosely, while the thread-feeding device which supplies filament 11 is adjusted to hold the filament very tightly, which will, after the loop has been formed by the needle, draw this particular filament tight around the 45 loop formed by the other filament.

It is obvious that this manner of knitting also lends itself to the production of various color effects. Furthermore, the volume, flexibility and softness of the yarn can be dimensioned in any

desired manner. And lastly, the cost of production of this type of fancy yarn is considerably reduced by my invention on account of the high output capacity of a knitting head compared with twisting or braiding devices. For instance, I have produced, per knitting head, yarns of the type illustrated in the present application at the rate of from 400 to 4000 yards per hour, depending upon the length of the loops formed.

It is understood that by the term "filament" 10 as used hereinabove and in the annexed claims, I mean an elongated element composed of one or more material fibres assembled as may be desired, in the same sense in which the term "thread" is used in my aforementioned Patent 15 No. 2,006,275.

I claim:-

1. Method of producing an interlocked-knitted yarn from a plurality of filaments, consisting in rotating a single knitting needle transversely to 20 its axis in a fixed circular path, supplying the filaments individually at given points into the path of said needle, and longitudinally reciprocating said needle at suitable intervals during each rotation a number of times equal to the 25 number of filaments supplied, to permit looping engagement of the needle successively with each of said filaments whereby yarn of successive, interlocked-knitted loops is formed from said filaments. 30

2. A device for producing an interlocked-knitted yarn from a plurality of filaments by a single knitting needle, comprising a needle cylinder, a single knitting needle longitudinally guided in said cylinder to permit longitudinal reciprocation therein, a cam ring concentrically disposed with respect to said cylinder and engaging said needle for longitudinally operating it to move its knitting hook beyond and below the cylinder rim when the cylinder rotates, and means for 35 supplying the several filaments at given points of the cylinder rim into the path of the needle, said cam ring having a number of spaced cams equal to the number of filaments supplied, to cause looping engagement of the needle successively with each of said filaments to produce a 40 yarn of successive, interlocked-knitted loops from said filaments. 45
